GRAIN DUSTING APPARATUS

Robert F. Berkner, Mahnomen, Minn.

Application September 20, 1950, Serial No. 185,790

4 Claims. (Cl. 21—109)

1

My invention relates to devices for the dusting of grain with germicidal powder for the purpose of rendering the individual kernels or grains resistant to disease, molds, and the like.

It is common practice to apply a fine dusting or coating of germicidal powder to grain for the above purpose through the medium of machinery, which either tumbles the grain in a powder by passing the grain through a stream of germicidal dust or a stream of powder-laden air. This process and the machinery involved is obviously rather expensive and objectionable from this point of view.

The primary object of my invention is the provision of a simple device for the dusting of grain with a germicidal powder while the grain remains in a static condition in sacks, bins, or the like—usually sacks.

A still further object of my invention is the provision of a device of the class described, which is relatively inexpensive to produce, which is light in weight, rigid in construction, and durable in use.

A still further object of my invention is the provision of a device of the class described, which is highly efficient and extremely easy to operate and control.

The above and still further objects of my invention will become apparent from the following detailed specification, appended claims, and attached drawings.

Referring to the drawings, wherein like characters indicate like parts throughout the several views:

Fig. 1 is a view in side elevation of my novel structure showing its use in a bag of grain, portions of said bag being broken away and shown in section;

Fig. 2 is a view in front elevation;

Fig. 3 is a transverse section taken on the line 3—3 of Fig. 2;

Fig. 4 is an enlarged vertical section of the upper portion of the device; and

Fig. 5 is a view corresponding to a portion of Fig. 4 but showing a different position of some of the parts thereof.

Referring with greater particularity to the drawings, the numeral 1 indicates, in its entirety, a container for germicidal powder having a hopper-like bottom 2 and closed at its upper end by a removable cover 3. Preferably and as shown, the cover is securely held in place by thumb nut-equipped bolts 4 which are pivotally secured as at 5 to bracket members 6 projecting laterally outwardly from the container 1 on opposite side

2

portions thereof in spaced relation to the cover 3. As shown, particularly with reference to Fig. 4, it will be noted that the bolts 4 are movable into and out of outwardly-opening slots 7 in ears 8, which project laterally outwardly from the cover 3 in opposite directions. To facilitate removal of the cover 3 from the container 1 when the bolts 4 are swung downwardly out of engagement with the slots 7, I provide an upstanding bail-like handle 9.

At its lower end portion, the container 1 is provided with a laterally-projecting tubular outlet passage 10 which forms an extension of the hopper 2 and which terminates in a port 11. The tubular outlet 10 defines a marginal valve seat 12 around the discharge port 11. Wall structure 13 defines a mixing chamber 14 outwardly of and surrounding the tubular discharge outlet 10 and the port 11. A valve stem in axial alignment with the outlet passage 10 is mounted for rotary and limited sliding movements in laterally-spaced bearings 16 and 17, the former of which is secured directly to the wall structure 13 and the latter of which is secured indirectly thereto by means of metal strips 18, one on each side of the stem 15. As shown, the inner end of the stem 15 projects inwardly of the wall structure 13 and axially into the tubular outlet passage 10 and is there provided with a valve 19 preferably formed from rubber-like material. Preferably and as shown, the valve 19 is provided with rigid face plates 20 and 21, all three being held in desired relationship by means of a nut 22 having screw-threaded engagement with the inner end of the stem 15.

For the purpose of imparting rotary movements to the stem 15, I provide a handle 23 which is journalled thereto and is provided with a pawl 24 which is biased toward engagement with teeth 25 fast on the stem 15. Longitudinal movements of the handle 23 with respect to the stem 15 are prevented by spaced bearing flanges 26, one on each side of the ratchet teeth 25. A coil compression spring 27 on the stem 15 intermediate the bearing 17 and the handle 23 yieldingly biases the valve 19 toward engagement with the seat 12. It will be noted that the radially outer portion of the bearing 17 is provided with cam teeth 28 which are adapted to intermesh with cooperating teeth 29 on a head 30 fast on the extreme outer end of the stem 15.

It will be noted that the rotary movement of the handle 23 and stem 15 is limited by contact of the handle 23 with the spaced strips 18. However, as the pawl 24 engages one of the ratchet

teeth 25 fast on the stem 15 and the handle 23 is then rotated within the limits above-described, limited rotary as well as longitudinal sliding movement is imparted to the stem 15, whereby to temporarily unseat the valve 19 from its seat 12 and allow a pre-determined amount of germicidal powder to drop into the mixing chamber through the port 11.

An agitator 31, of serpentine formation and shown as being in the nature of a convoluted length of wire, is secured at one end to the nut 22 and projects generally axially of the stem 15 into the hopper-like bottom 2 of the container 1. The compound rotary and longitudinal movements of the agitator 31 adequately agitate the germicidal powder Y and prevent caking of the same. The serpentine agitator illustrated is particularly desirable because of its low cost and simple construction and the fact that it functions as a result of longitudinal reciprocating movements or rotary movements or both. However, it will be understood that other agitator designs which operate as a result of longitudinal reciprocating movements or rotary movements or both may be employed.

Means for delivering air under pressure to the mixing chamber 14 is provided by a tubular conduit 32 which is welded or otherwise rigidly secured between a pair of laterally-spaced reinforcing flanges 34. The inner end of the conduit 32 extends through an aperture 35 in the wall of the mixing chamber 14 and terminates in a down-turned end 36, which is directed toward and is in alignment with an elongated tubular nozzle 37 having perforations 38 at its lower end. At its outer end, the conduit 32 is provided with a valve 39 having a handle 40, at its under side, which is adapted to engage a plunger 41 and unseat the same under upward movements of the handle 40. To facilitate operation of the valve 39, I provide a generally inverted U-shaped reactance member 42 which projects laterally outwardly from the side of the container 1.

Fig. 11 illustrates the position which my novel structure takes in the dusting of grain A in a sack X. In order that the grains A in the lower portion of the sack X be subjected to a thorough dusting, the handle 23 is oscillated about the axis of the valve stem 15, whereby to intermittently impart limited rotary and longitudinal movements to the valve 19 as the pawl 24 associated with the handle 23 engages the ratchet teeth 25 on the stem 15. Such oscillation causes the cam teeth 28 to ride up on the cam teeth 29 against the bias of the coil spring 27, as shown in Fig. 5. In this position, the valve is open and the germicidal powder Y is being dropped into the mixing chamber 14 through the port 11. When the cam teeth 28 and 29 are snapped into the nesting position of Fig. 4, the valve 19 is forced against the annular seat 12, as there shown. At substantially the same time as the germicidal powder Y is being deposited into the mixing chamber 14, by manipulation of the handle 23, the air valve 39 is opened by applying the hand between the handle 40 and reactance hood 42. When this happens, the germicidal powder Y comes out of the perforations 38 of the tubular nozzle 37 with sufficient force to assure that a large area of grain A is dusted. Dusting of the grain in the upper portion of the sack X may be accomplished merely by positioning of the perforate end of the nozzle 37 in the general area.

My invention has been thoroughly tested and

found to be completely satisfactory for the accomplishment of the above objects; and, while I have shown a preferred embodiment of my novel structure, it will be seen that the same is capable of modification without departure from the spirit and scope of the invention as defined in the claims.

What I claim is:

1. In a device of the class described, a hopper defining a discharge port in its lower end portion and a marginal valve seat around said port, wall structure outwardly of said port defining a mixing chamber, a valve stem mounted in said wall structure for longitudinal sliding movements, a valve on the inner end of said stem movable into and out of engagement with said valve seat upon longitudinal sliding movements of said stem, yielding means biasing said valve toward engagement with said valve seat, means for delivering air under pressure into said mixing chamber, an elongated tubular injection nozzle projecting downwardly from the mixing chamber, means for imparting limited longitudinal movements to said valve stem to unseat said valve, and agitator means associated with said valve and extending into said hopper for common movements with said valve, said agitator being of a kind which will agitate material in the hopper as a result of either longitudinal reciprocating movements or rotary movements or both.

2. In a device of the class described, a hopper defining a laterally-opening discharge port in its lower end portion and a marginal valve seat around said port, wall structure outwardly of said port defining a mixing chamber, a valve stem mounted in said wall structure in axial alignment with said port for rotary and limited longitudinal sliding movements, a valve on the inner end of said stem movable into and out of engagement with said valve port upon longitudinal sliding movements of said stem, said mixing chamber being provided with a hopper-like bottom which feeds into a tubular nozzle depending therefrom, means delivering air under pressure into said mixing chamber, said means terminating in a tubular outlet directed toward and in axial alignment with said tubular nozzle, means yieldingly biasing said valve toward said valve seat, means for imparting longitudinal movements to said valve stem whereby to unseat the same against bias of said yielding means, and an elongated serpentine agitator operatively associated with said valve and extending into and resting upon the lower end portion of said hopper and movable with said valve.

3. In a grain dusting device, a hopper defining a discharge port in its lower portion and a marginal valve seat around said port, wall structure outwardly of said port defining a mixing chamber, a valve stem mounted in said wall structure for rotary and longitudinal reciprocating movements, a valve mounted on said valve stem for reciprocating movements therewith to and from port-closing position against said marginal valve seat, an agitator mounted fast on the valve stem for common rotary and reciprocating movements therewith and projecting into said hopper, means for delivering air under pressure into the mixing chamber, an injection nozzle projecting downwardly from the mixing chamber, and means for imparting compound rotary and longitudinal reciprocating movements to the valve stem to intermittently move the valve to and from the port-closing position and operate said agitator,

said agitator being of a kind which will agitate material in the hopper as a result of either longitudinal reciprocating movements or rotary movements or both.

4. The structure defined in claim 3 in which the said agitator is of serpentine formation and closely overlies the lower portion of the hopper.

ROBERT F. BERKNER.
